UNITED STATES PATENT OFFICE.

RICHARD CHOINANUS, OF HOBOKEN, NEW JERSEY, ASSIGNOR TO HERMAN OPPENHEIMER, OF NEW YORK, N. Y., AND ABRAHAM BONNEM, OF OBERSTEIN, GERMANY.

HOLDER FOR PICTURES.

SPECIFICATION forming part of Letters Patent No. 368,994, dated August 30, 1887.

Application filed April 11, 1887. Serial No. 234,541. (No model.)

To all whom it may concern:

Be it known that I, RICHARD CHOINANUS, a subject of the Emperor of Germany, and a resident of Hoboken, in the county of Hudson and State of New Jersey, have invented certain new and useful Improvements in Holders for Pictures, &c., of which the following is such a full, clear, concise, and exact description as will enable others skilled in the art to which my invention appertains to make and use the same, reference being had to the accompanying drawings, forming part of this specification.

Holders and frames for pictures, ornamental cards, and the like have heretofore been made with a front and back piece, the back piece being connected to the front in such a way as to form a support or leg, so that the holder will stand upon a mantel or other flat surface. These holders have sometimes been mere frames, and sometimes they have been skeleton like, being made of metal. In most instances, however, difficulties have been experienced, owing to a want of the proper adjustability of the same to the pictures which they are made to hold—as, for example, if a picture be slightly longer than the holder it cannot be used without trimming or cutting, which of course is not at all desirable; and, moreover, when such holders have been made of metal they have been somewhat costly, owing to the number of parts and amount of work required to manufacture them.

The object of my invention is to make a simple, cheap, and adjustable picture-holder of wire or flexible metal; and the invention consists in the construction of the same, as hereinafter more fully described and claimed.

In the drawings, Figure 1 is a perspective view of a picture-holder constructed according to the requirements of my invention, and Fig. 2 is a cross-section taken on the line *xx* of Fig. 1.

In order to make this holder, I take flexible metal, preferably wire, and form the front piece, *A*, with its hooks for holding the picture, out of one piece of metal. This is done by bending the wire so that the ends form hooks *b b*, which serve to support the lower end of the picture, and the bends or elbows

of the hooks act as legs, upon which the frame *A* rests. After such bends are formed, or before, as may be desirable, the wire is curved somewhat in the form, on the right-hand side, of the letter *S*, after which it extends upward and is bent into the form of a double hook, *a*, which then permits a continuation of the bending, so that a reverse *S* is made upon the left-hand side, and the end thereof forms a hook, *b*, as shown. This bending of the wire gives it somewhat the form of rings, which impart elasticity to the holder, so that it may be adjusted to the size of the picture, and the curved portions act as wings, which support the back of the picture between the ends held by the hooks; but I prefer to solder the parts of the wire which come together between the upper springs and also between the lower springs, in order to make the holder more firm and to retain its shape.

The back *B* may be formed of a single piece of wire having a *U*-shaped collar, *C*, to the back portion of which collar the support *B* is fastened by soldering or otherwise, and a pin, *c*, is secured to the wires which form the frame *A*, such pin *c* being made to pass through the ears of the collar *C*, as shown, thus forming an axis or hinge for the back or support *B*, which is thus free to swing out when it is desired to set the holder upon a mantel or other base.

By making the front piece of a single piece of metal, with springs, as described, the holder is elastic and may be lengthened or shortened, as desired, the pictures being held by the hook *a* at the top and the hooks *b b* at the bottom. The cost of manufacture is cheapened by such way of forming the same. Of course the particular design shown may be varied according to fancy, but I have shown a simple form of the same.

Having thus described my invention, what I claim as new, and desire to secure by Letters Patent, is—

1. A holder for pictures, formed of a single piece of flexible metal, as wire, the two ends and center whereof are bent into hooks adapted to retain the picture, said wire being also curved intermediate between said hooks, as in ring forms, which are adapted to afford a rest

for the back of the picture and to impart elasticity to said holder, substantially as set forth. 2. A holder for pictures, consisting of a front piece of flexible metal, as wire, the ends and center whereof are bent into hooks adapted to retain the picture, said wire being also curved intermediate between said hooks, as in ring forms, which are adapted to afford a rest for

the back of the picture, in combination with a support hinged or secured to said front piece, substantially as described.

RICHARD CHOI NANUS.
